COMBINED BELL AND SUPPORT THEREFOR

Walter Koziol, Russell, Ill., assignor to Charglow Manufacturing Co., Antioch, Ill., a corporation of Illinois

Filed Jan. 28, 1969, Ser. No. 15,537

Term of patent 14 years

Int. Cl. D29—99

U.S. Cl. D72—1

What is claimed is:

The ornamental design for a combined bell and support therefor, substantially as shown and described.
